Philip Hittel.

Letter Patent.

The Schedule referred to in these Letter Patent, and making part of the same, containing a description in the words of the said Philip Hittel himself, of his improvement in the Truss called the improved common convex Truss.—

The deficiency experienced for the want of a good Truss for the proper support of the Protuberance viscera in hernial affections and ultimately performing a radical cure will always render an investigation of this painful malady interesting. Before describing my improvement, I shall briefly state some of the imperfections attending all other Trusses. 1st in all cases where the person is ruptured on one side (speaking generally), in common practice the Truss is alone applied to the affected side. Now experience has undoubtly confirmed that what is may have been the cause of rupture, either by violence, exertion or by a predisposition of weakness of the parts. Id, or that in all cases of aggravated or scrotal Hernia where such pressure is requisite for the retention of the intestine as to change the internal position of any of the abdominal viscera from the position, which nature alone adapted. It is evident the weight or force undoubtedly will predominate to the opposite side and will cause or facilitate the production of another rupture, which would not have occurred under any other circumstances of ordinary exertions; 2^d by the anecd description of my improved Truss I believe all the objections to other Trusses are obviated in my improvement, which consists of two small boards or blocks of wood, ivory, or any other material may be substituted, between 1 or 1.5 inches long, one inch thick, and sufficiently broad to extend to each groin, curved in the shape of the upper half of a heart, flat on the outside and convex on the inner and extreme ends of the upper sides. In carving the inner side great care will be requisite in forming the projection immediately at the extreme ends in order that it makes the principal pressure on the neck immediately at the rupture which in order to accomplish the part curved on the inner sides precisely resembles a gord, with the stem projecting downwards whilst the inner and lower edge is carved flat with a hollow in the middle of the lower part.

294.

So as to seat without producing any uncomfortable pressure in the pubis, or point, joined in the centre by a hinge in order to adapt itself the more ready, to the different position of the body, or the principle of applying the two convex or gun-shaped pads may, if preferred, be united by extending a piece of brass or tin fastened on each end of the pads, by means of a screw in the center, of this plate, the spring should be fastened by means of a rivet or a small brass screw can be substituted, by which means the person can more readily lengthen or shorten the spring as the case may require. Being now finished, the whole should be covered simply with buckskin after which you fasten the one end of the spring on the scripture, pad, or portion thereby, making lateral pressure on the other portion or side, when placing the spring around the body and for the better security a bandage may be attached to the back pad passing it around the other portion of the body and fastened by means of a knob on the front pad. By this improved common convex trap I claim every principle of equal pressure of the convex pad, curved or cast on a plate of any material whatsoever, united in the centre by a hinge thereby, making equal pressure, with the largest diameter of the convex portion above, gradually lessening downwards whilst giving general support to the lower parieties of the abdomen agreeably to the accompanying specification and drawings all which I find to answer perfectly well.—
